UNITED STATES PATENT OFFICE.

MARION STUART PLUMLEY, OF PITTSBURGH, PENNSYLVANIA, ASSIGNOR TO SUPERIOR OXYGEN COMPANY, OF PITTSBURGH, PENNSYLVANIA, A CORPORATION OF PENNSYLVANIA.

WELDING-TORCH.

1,173,461.

Specification of Letters Patent. Patented Feb. 29, 1916.

Application filed December 24, 1914. Serial No. 878,841.

To all whom it may concern:

Be it known that I, MARION STUART PLUMLEY, a citizen of the United States, residing in the city of Pittsburgh, county of 5 Allegheny, and State of Pennsylvania, have invented certain new and useful Improvements in Welding-Torches, of which the following is a specification.

My invention relates to new and useful 10 improvements in welding torches of that character or type constructed to burn a mixture of oxygen and acetylene, or other inflammable gas, to produce a flame of proper temperature for use in the welding of 15 metals.

The objects of the invention are to provide a torch of the character mentioned which will be extremely simple in construction, efficient in operation, and in which the 20 parts may be readily taken apart for repair or readjustment.

A further object is to provide an improved form of handle for a torch.

The invention consists in the improvements to be more fully described hereinafter and the novelty of which will be particularly pointed out and distinctly claimed.

I fully and clearly illustrate my invention in the accompanying drawings to be taken 30 as a part of this specification, and wherein:

Figure 1 is a view in side elevation of a preferred embodiment of my invention. Fig. 2 is a plan view of the construction shown in Fig. 1, partly in section, and with 35 parts broken away. Fig. 3 is a vertical central longitudinal section through the torch head. Fig. 4 is a longitudinal central section through a control valve. Fig. 5 is a transverse section through the control valve 40 shown in Fig. 4. Fig. 6 is a transverse section on the line 6—6 of Fig. 1.

Referring to the drawings by characters of reference, 1 designates a torch head which may be formed in one integral piece or in 45 two pieces as shown in the drawing, and provided with a longitudinal bore 2 constituting a mixing chamber and also an outlet duct for the inflammable mixture to constitute the heating flame. This duct 2 opens 50 at one end through an end of the said head, as at 3, and at its opposite or inner end opens into an intermediate chamber 4, said chambers 2 and 4 being preferably separated by a constricted passageway 5. At its end 55 opposite from that opening into the passageway 5, the chamber 4 is surrounded by a shoulder 6, beyond which the head 1 is formed with a circular recess 7, said recess joining at its rear end with a socket 8 opening through the extreme rear end of the 60 head and having its inner wall threaded, as at 9. Extending through the chamber 4 is an injector nozzle 10, the delivery end of which opens into said constricted passageway 5, and the rear end of which is formed 65 with an enlargement 11, preferably closely fitting the walls of the recess 7 and provided with an intermediate shoulder 12, adapted to be seated upon the shoulder 6, heretofore described. Threaded into the said socket 8 70 is a perforated plug 13 adapted to engage the rear end of said enlargement 11 on the injector nozzle so as to hold the latter firmly in position against the said shoulder 6, heretofore described. The opening or perforation 75 through the plug 13 is shown at 14, and provides for communication between the socket 8 and the bore 15 of the injector nozzle. The rear end of the socket 8 is closed by a suitable closure preferably in the form 80 of a screw plug 16 threaded into engagement with the threads 9, said plug being of such length that, when it is screwed into place, its inner end terminates short of the plug 13 so as to provide a chamber between 85 said plug and the perforated plug 13. The outside diameter of that portion of the injector nozzle 10 which extends through the chamber 4 is preferably made less than the diameter of said chamber, so that an annular space 17 is provided between the injector nozzle and the wall of the chamber, for a purpose to be presently set forth. The head 1 is provided with upper and lower pipe nipples 18, 19, formed integral with 90 said head and opening respectively into the socket 8 and the chamber 4, heretofore described. The nipple 18 is adapted to be connected to a supply pipe for supply of oxygen, and the nipple 19 is adapted to be 95 connected to a supply pipe for acetylene or proper combustible gas.

I preferably provide simple and effective means whereby the nipples 18, 19, may be detachably connected to the supply pipes. 105 Each of these nipples is provided with exterior threads 20 and internal cone sockets 21, which sockets are adapted to receive flanged cone heads 22 on the supply pipes 23, 24, respectively, said heads and nipples 110

being connected by flanged nuts 24^a engaging the threads 20 and the flanges on said cone heads. By this arrangement the head may be quickly attached to and detached 5 from the supply pipes 23, 24. The pipes 23, 24, are connected at their rear ends to a double valve casing 25 adapted to be connected by nipples 26, 27, respectively, to suitable sources of combustible gas and 10 oxygen. In the valve casing 25 is a turn plug 28 having cross passages 29, 30, by means of which flow through the valve to the pipes 23, 24, is simultaneously controlled.

In the acetylene supply pipe 23 is interposed a turn plug casing 31, said casing containing a turn plug 32, by means of which the flow is controlled relative to the supply of oxygen. The turn plug is provided with a rearwardly extending stem or handle 33, 20 extending rearward in convenient relation to the handle 34, whereby the operator, when grasping the handle 34, may conveniently operate the acetylene control turn plug with his thumb.

25 The handle 34 is located between the valve casing 25, and the casing 31 and is preferably composed of two similar sections, each consisting of a semi-cylindrical hollow body 35, having end walls 36, said end walls being each provided with recesses 37, so that, when the parts 35 are assembled on the pipes 23, 24, a hollow cylindrical handle is provided in which the end walls abut so that the recesses 37 form spaced openings 38 rounding the pipes 23, 24, and maintaining them in parallel relation. The handle sections 35 may be secured together in any suitable manner, but preferably by clamping screws 39 extending through registering 40 bosses or sleeves 39 formed integral with the inner faces of the said sections. By this arrangement I provide a handle which is easy to grasp, and which not only is maintained cool because of its hollow structure, 45 but also serves to maintain the rigidity of the pipes 23, 24, and hold them in parallel relation.

In operation the operator turns the turn plug 28 to permit simultaneous flow of acetylene and oxygen to the pipes 23, 24, the 50 oxygen flowing freely to the upper end of the head 1 and entering the socket chamber 8, flowing from said chamber under pressure through the injector toward the mixing chamber 2. The operator with his thumb

swings the valve handle 33 to permit the desired amount of acetylene or other combustible gas to flow through the pipe 23, through the nipple 19, into the chamber 4, by the space 17 surrounding the injector nozzle, 60 and the pressure of oxygen entrains the acetylene gas and by its injector action on the nozzle 10 causes the acetylene gas to flow with it through the constricted passage 5 into the chamber 2, the two gases being thoroughly mixed in the passage 5 and said mixing chamber. A wire gauze 38' may be placed between the plug 13 and the rear end of the enlargement 11 of the injector to prevent any particles of dirt or grit from 70 entering the latter.

What I claim and desire to secure by Letters Patent of the United States is:—

1. A welding torch head having a longitudinal mixing chamber, an outlet from the 75 mixing chamber at one end of the head, an intermediate chamber at and opening into the inner end of the mixing chamber, a shoulder surrounding said intermediate chamber, an injector seated on said shoulder and extending through said chamber and delivering into the mixing chamber, said body having a threaded socket in rear of the injector, a perforated plug threaded into 80 said socket and engaging the rear of the injector, and a closure for the socket, said body having inlets leading respectively to said intermediate chamber and said socket.

2. A welding torch head having a longitudinal mixing chamber, the walls of said chamber being constricted toward each end thereof, an outlet from the mixing chamber at one end of the head, an intermediate chamber at and opening into the inner end of the mixing chamber, an injector seated 90 in said intermediate chamber and having its nozzle delivering into the mixing chamber, a threaded socket in rear of the injector, a closure plug threaded into the socket and spaced from the injector, and inlets leading 95 respectively to said intermediate chamber and said socket.

In testimony whereof I have hereunto signed my name in the presence of two subscribing witnesses.

MARION STUART PLUMLEY.
